No. 802,709.

PATENTED OCT. 24, 1905.

A. C. PREBLE.

FIRE DOOR.

APPLICATION FILED JUNE 30, 1905.

UNITED STATES PATENT OFFICE.

ANDREW C. PREBLE, OF CHICAGO, ILLINOIS.

FIRE-DOOR.

No. 802,709.

Specification of Letters Patent.

Patented Oct. 24, 1905.

Application filed June 30, 1905. Serial No. 267,705.

To all whom it may concern:

Be it known that I, ANDREW C. PREBLE, a citizen of the United States, residing at Chicago, in the county of Cook and State of Illinois, have invented a new and useful Improvement in Fire-Doors, of which the following is a specification.

My invention relates particularly to fire-doors having vertically-moving separable upper and lower sections; and my primary object is to provide improved fire protection at the upper edge of the upper section and at the lower edge of the lower section, thereby overcoming serious defects in present construction.

My invention is illustrated in its preferred embodiment in the accompanying drawings, in which—

Figure 1 represents a broken vertical section of a wall of an elevator-shaft equipped with my improved fire-door, and Fig. 2 a broken horizontal section taken as indicated at line 2 of Fig. 1.

In the preferred construction A represents a wall of an elevator-shaft A', B a door-opening, and C my improved door applied thereto. The door-opening is surmounted by a lintel composed of I-beams b and a metal plate b' beneath the I-beams. The inner edge of the plate b' projects slightly beyond the inner surface b² of the wall A and has supported thereon a horizontal angle-bar b³, having a horizontal flange b⁴ and a vertical flange b⁵. At the bottom of the door-opening is the floor b⁶, upon which is secured a sill-plate b⁷. The inner edge of the plate b⁷ projects beyond the inner edge of the wall A and has secured to it an angle-bar b⁸, having a horizontal flange b⁹ and a downturned vertical flange b¹⁰. Adjacent to the angle-bar b⁸ is an angle-bar b¹¹, having a downturned flange b¹², separated from the flange b¹⁰ by a space b¹³. At the sides of the door are provided the usual vertical guides b¹⁴ for the lateral edges of the door.

The door C comprises an upper section C' and a lower section C'', which are vertically movable in the guides b¹⁴. In practice the door-sections are connected with each other in a well-known manner to counterbalance each other. The upper door-section C' is preferably formed of corrugated sheet metal c, which has connected with its lateral edges angles c', (one shown,) with which are connected angles c'', having flanges engaging

the guides b¹⁴. The lower edge of the upper door-section is equipped with an angle c³, with which is connected a bar c⁴. The lower door-section is similarly formed and connected with the guides b¹⁴ and has at its upper edge an angle c⁵, which slidably engages the depending portion of the bar c⁴, forming the usual fireproof joint at the meeting edges of the door-sections. The upper section is equipped at its upper end with an angle-bar c⁶, which has a horizontal flange c⁷ turned toward the elevator-shaft. Secured upon the flange c⁷ is an angle c⁸, having a downturned flange c⁹, which when the door is closed hooks over the flange b⁵ of the angle b³. The lower door-section is equipped at its lower edge with an angle-bar c¹⁰, having a horizontal flange with which is connected an angle-bar c¹¹, having an upturned flange c¹², which hooks under the flange b¹⁰ of the angle-bar b⁸.

From the foregoing description it will be understood that when the door-sections are closed fireproof joints are afforded at the upper and lower edges of the upper and lower door-sections, respectively, as well as at the lateral edges and the meeting edges of the door-sections. It is understood, of course, that when the upper door-section is raised the lower door-section is lowered in opening the door.

What I regard as new, and desire to secure by Letters Patent, is—

1. The combination with a wall having a door-opening and vertical guides at the sides of said opening, of vertically-movable upper and lower door-sections movable in said guides, a member connected with the upper edge portion of the upper door-section bearing a downturned flange, a stationary member at the upper portion of the door-opening having an upturned flange over which said first-named flange hooks, a member connected with the lower edge portion of the lower door-section having an upturned flange, and a stationary member at the lower portion of the door-opening having a downturned flange under which the flange of said last-named member hooks, for the purpose set forth.

2. The combination with a wall having a door-opening and a lintel at its upper portion equipped with a plate, of an angle-bar supported upon the inner edge portion of said plate and having an upturned flange, a vertically-movable upper door-section equipped

with an angle-bar having a downturned flange hooking over said first-named flange, a sill-plate at the bottom of the door-opening, an angle-bar secured thereto having a downturned flange, and a vertically-movable lower door-section equipped with an angle-bar having an upturned flange hooking under the flange

of said last-named angle-bar, for the purpose set forth.

ANDREW C. PREBLE.

In presence of—

L. HEISLAR,
J. H. LANDES.
